UNITED STATES PATENT OFFICE.

SAMUEL WANARY DENTON, OF BRONWOOD, GEORGIA.

BAGGING-MEASURING MACHINE.

1,093,037.

Specification of Letters Patent. Patented Apr. 14, 1914.

Application filed October 18, 1913. Serial No. 796,011.

To all whom it may concern:

Be it known that I, SAMUEL W. DENTON, a citizen of the United States, residing at Bronwood, in the county of Terrell and

5 State of Georgia, have invented certain new and useful Improvements in Bagging-Measuring Machines, of which the following is a specification, reference being had to the accompanying drawings.

10 This invention relates to certain improvements in bagging measuring machines and relates more particularly to the prior patent of myself and others, No. 485,491, dated November 1st, 1892, and the object of the 15 invention is to provide novel means whereby the requisite tension may be imparted to the bagging to assure its proper travel around the uppermost measuring roller.

The invention consists in the details of 20 construction and in the combination and arrangement of the several parts whereby certain important advantages are attained and the device is rendered simpler, less expensive and otherwise more convenient and advantageous for use, all as will be hereinafter 25 more fully set forth.

The novel features of the invention will be carefully defined in the appended claims.

30 In order that my invention may be the better understood, I will now proceed to describe the same with reference to the accompanying drawings, wherein—

Figure 1 is a view in front elevation of a bagging measuring machine constructed in accordance with an embodiment of my invention; Fig. 2 is a view in side elevation of the device as disclosed in Fig. 1; Fig. 3 is an enlarged fragmentary view in front elevation illustrating certain details of the invention, as herein disclosed; and Fig. 4 is an enlarged fragmentary view in side elevation.

The construction illustrated in the accompanying drawings is similar to that disclosed in the prior patent referred to and a 45 detail thereof is believed to be unnecessary other than to identify the intimate parts with which my present improvement coats.

As disclosed in the accompanying drawings, *a a* denote the main supporting uprights, the upper ends of which are slotted for the reception of the journals of the removable shaft *b*, carrying the bagging to be unwound and measured and cut. The 50 measuring rollers *c d* are journaled one above the other at points below the bagging shaft, the bagging being adapted to pass around

the upper roller *c* and between both of such rollers *c* and *d* to be properly engaged by the cutting mechanism identified as a whole by 1.

Each of the uprights *a* at a point above the uppermost roller *c* but in close proximity thereto is provided with the transversely disposed segmental slot 2 adapted to afford a mounting for the shaft 3 of the 60 roller 4 which is adapted to be positioned above the stretch of the bagging leading from the shaft *b* to the rollers *c* and *d*, such shaft serving to create the requisite tension on such stretch of the bagging as to assure 65 its proper engagement by the uppermost roller *c*. It is further to be observed that the extent of the slots 2 are substantially entirely to one side of the axial center of the rollers *c* and *d*, whereby it will be observed 70 that the roller 4 will result in a greater portion of the bagging contacting with the roller *c*. By the provision of this roller, it will be observed that the bagging may be measured with accuracy and facility irrespective of the condition in which it may be wound, as the movement of the roller 4 within the slots 2 serves to compensate for any looseness that may occur in the roller 75 which would otherwise tend to slip.

80 While the weight of the roller 4 itself may be depended upon to accomplish this function, I prefer to have the end portions of the shaft 3 projected through the end portions of the section 5 of the bell levers 6 pivotally connected at their heel portions, as at 85 7, to the inner faces of the uprights *a*, the pivotal points of such bell levers being at the axial center of the slots 2 whereby any movement imparted to the bell levers 6 will 90 cause the shafts 3 to properly travel therein. The upper sections 8 of the bell levers are caused to project forwardly of the uprights *a* and are united or connected by the transverse bar 9, whereby it will be readily perceived that should the occasion require that the tension on the stretch of the bagging be relieved that by forcing the connecting bar 9 upwardly the pressure of the roller 4 on the stretch may be relieved. It will also be 95 observed that this connecting rod 9 will serve to afford additional weight for the roller 4 and further assure its proper contact with the bagging. It is preferred that this connecting rod 9 be produced of metal 100 although it is thought to be obvious, without a disclosure in the drawings, that any 110

material may be employed and the requisite weight be created by the application thereto of suitable weights.

From the foregoing description, it is thought to be obvious that a bagging measuring machine constructed in accordance with my invention is of an extremely simple and comparatively inexpensive nature and is particularly well adapted for use by reason of the additional tension created upon the bagging to assure its proper engagement with the measuring rollers, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. In a measuring and cutting machine for bagging, the combination of a frame including uprights provided with segmental slots disposed substantially transversely thereof, measuring rollers mounted between the uprights and below the slots, the axial centers of such rollers being to one side of a vertical line through the slots, a tension

roller mounted in such slots, bell levers pivotally supported by the uprights and operatively engaged with the tension roller, and a rod connecting such bell levers whereby they may be caused to be manipulated in unison.

2. In a measuring and cutting machine for bagging, the combination of a frame including uprights provided with segmental slots disposed substantially transversely thereof, measuring rollers mounted between the uprights and below the slots, the axial centers of such rollers being to one side of a vertical line through the slots, a tension roller mounted in such slots, bell levers pivotally supported by the uprights and operatively engaged with the tension roller, and a weighted connection between such bell levers whereby the requisite straining action is imparted to the tension roller, such connection also affording a means whereby the bell levers may be caused to be manipulated in unison.

In testimony whereof I hereunto affix my signature in the presence of two witnesses.

SAMUEL WANARY DENTON.
